UNITED STATES PATENT OFFICE.

JOHN STURGUS BRADLEY, OF NEW CONCORD, OHIO.

COMPUTING-SCALE.

No. 909,743.

Specification of Letters Patent.

Patented Jan. 12, 1909.

Application filed July 25, 1908. Serial No. 445,337.

To all whom it may concern:

Be it known that I, JOHN STURGUS BRADLEY, a citizen of the United States, residing at New Concord, in the county of Muskingum and State of Ohio, have invented certain new and useful Improvements in Computing-Scales, of which the following is a specification.

My invention relates to the improvement 10 of computing scales and has particular relation to the improvement of suspended or depending scales.

The objects of my invention are to provide an improved construction of suspended scale 15 comprising means for equalizing the downward pull or depression on two opposing scale beams, regardless of the position of the weight on the hanging tray and to otherwise so construct my improved scale mechanism 20 as to insure a uniform and accurate movement of the parts thereof under varying conditions. These objects I accomplish in the manner illustrated in the accompanying drawing, in which:

25 Figure 1 is a view partly in section and partly in elevation of my improved scale construction, Fig. 2 is a sectional view on line $a-a$ of Fig. 1, Fig. 3 is an enlarged sectional view on line $y-y$ of Fig. 1, Fig. 4 is an enlarged detail view illustrating the pivotal support of the inner end of one of the beams which I employ in the manner hereinafter described, and, Fig. 5 is a detail plan view of the rear portion of one of the 35 scale beams.

Similar numerals refer to similar parts throughout the several views.

1 represents a casing or exterior frame of suitable form and which is provided in its 40 central portion and upper side with means for suspending the same, which may be in the nature of an opening such as is shown at 2. Rising from the floor or upper side of the base of the casing 1 near each end of the latter is a fixed supporting standard 3, the upper end of each of which is provided with crossed bifurcations or recesses, which bifurcations are indicated respectively at 3^a and 3^b in Fig. 5 of the drawing. Through 45 each of the bifurcations 3^a extends the lower and outer portion of a scale beam 4, the latter being provided on opposite sides with knife blade bearing projections 5, the lower edges of which bear in the centers of V-shaped recesses formed in the upper sides of bearing members 6 which are of agate or

other exceedingly hard material and which are mounted in the bifurcations 3^b on opposite sides of the beam.

Each of the beams 4 has depending therefrom adjacent to its standard 3, a hanger 7 the upper bifurcated portion of each of the hangers embracing opposite sides of the beam and being supported therefrom through the medium of knife blade bearing 60 projections 8 of the beam, the upper edges of which engage bearing members 9 mounted in oppositely located recesses or openings in the upper portion of the hanger. The lower ends of the hangers 7 are pivotally connected 70 as indicated at 7^a with the ends of a horizontal supporting bar 10, the latter being parallel with the base of the casing 1 and having a central depending hook 10 a which projects through a central bottom opening 1 a in the 75 casing 1. With the hook 10 a is adapted to be engaged the bail 11 a of a suitable form of weighing tray 11 which is thus suspended beneath the casing 1.

Above the inner end portion of each of the 80 beams 4 I support in connection with the frame or casing 1, a bar 12 and from said bars project inwardly or toward each other, bearing or suspension brackets 13. Each of the bracket projections 13 is bifurcated to 85 receive a weight carrying head 14, which is of a substantially cam shape and the upper side of which is curved or rounded, as shown, said curved or rounded portion being extended inwardly from the body of said 90 head. Each of the heads 14 has projecting therefrom, oppositely located knife blade bearings 15, the lower edges of which are supported in the centers of the V-shaped recesses of bearing members 16 which are supported in the recessed or bifurcated sides of the bracket 13.

With the underside of each of the heads 14, is rigidly connected a downwardly extending rod 14 a which carries on its lower 100 end a bifurcated or slotted weight 17, the latter embracing loosely opposite sides of a beam 4. With the upper curved side of each of the heads 14 is connected a flexible metallic strap 18, which running over the curved 105 surface of said head, depends vertically therefrom, as shown, and is connected at its lower end with a hanger 19. As indicated in the drawing, each of these hangers 19 comprises an elongated vertically disposed 110 body having upper and lower parallel openings 20 and 21, the upper opening 20 having

- a V-shaped bearing recess in its upper side and the lower opening 21 having a corresponding although inverted bearing in its lower portion. As shown, the inner and 5 smaller end portions of the beams 4 extend through the hanger openings 21, said beams being provided with bearing projections 22 which engage the bearing recesses in the lower portions of said openings.
- 10 Between the inner ends of the beams 4 and below the latter, I suitably support from the framework or casing, a vertically disposed dash pot or cylinder 23 which is of the usual construction employed in the cushioning of 15 the movement of a piston contained therein. 24 represents the dash pot piston, the upper end of which is connected with the lower end of an upwardly extending rack bar 25. Above the dash pot the bar 25 is provided 20 with an opening 25^a through which passes a horizontal balance rod 26, the latter being formed with a central knife edge bearing projection, which bears in the bottom of the opening 25^a. Each end of the rod 26 has on 25 its upper side a similar bearing projection, which contacts with the upper side of the opening 20 in the corresponding hanger 19 through which the rod 26 projects. Above the rod 26, the bar 25 is bent rearwardly and 30 thence upwardly, its toothed surface engaging a toothed segment 27 carried by a horizontally disposed chart cylinder 28 which is pivoted in the upper portion of the casing 1 between frame members 29. The chart cylinder 28 is of the usual or well known construction and is adapted to have printed thereon weight and price indications which are visible as usual through an opening 30 in said cylinder. In order to properly guide 35 the bar 25 in its vertical reciprocating movement, I have provided a pair of guide pins 31 which extend on opposite sides of the lower portion of the bar 25 and which project from the casing 1.
- 40 In operation, it will be understood that when a weight is placed on the tray 11, the downward pull on the bar 10 will result in a corresponding and uniform downward swinging movement of the inner ends of the 45 beams 4 which movements will result in corresponding downward movements of the hangers 19 and supporting straps 18, with
- the result that the weights 17 will be swung upward and outward away from each other. The downward movements of the hangers 19 55 will also result in a downward movement of the rod 26 and a corresponding movement of the rack bar 25, thereby resulting in a partial rotation of the cylinder 28 and bringing to view proper chart indications through the 60 opening 30.
- It will readily be understood that although the weight applied to the tray, may be at one side thereof, the construction and connections of the various parts of my device will 65 insure the distribution of the downward pulling action on both the scale beams and the parts connected therewith, equally. It will thus be understood that a sensitive and accurate weighing mechanism is provided and 70 that the means employed are simple and positive in their actions.
- What I claim, is:
1. In suspension scales, the combination with a framework, two opposing pivoted 75 scale beams, a hanger depending from each of said beams, a bar connecting said hangers, and a weighing tray supported centrally from said bar, of an indicator or chart operating bar and connections between said operating bar and said scale beams whereby the movement of the latter imparts a predetermined degree of movement to said operating bar.
  2. In suspension scales, the combination 85 with a framework, a pair of oppositely located pivoted scale beams within said framework, a bar jointedly connecting the outer portions of said scale beams and a weighing tray suspended centrally from said bar, of a 90 pair of pivoted weight carrying heads above the beams, weights depending therefrom, straps connecting said weight carrying heads with the inner ends of said beams, a connection between said straps, and a scale chart 95 operating bar connected with said strap connection.

In testimony whereof I affix my signature in presence of two witnesses.

JOHN STURGUS BRADLEY.
